UNITED STATES PATENT OFFICE

98,124

DESIGN FOR A COMBINED WASHING MACHINE CASING AND WRINGER

Arthur H. Peters, Fort Wayne, Ind., assignor to
Horton Manufacturing Company, Fort Wayne,
Ind., a corporation of Indiana

Application November 29, 1935, Serial No. 59,838

Term of patent 7 years

To all whom it may concern:

Be it known that I, Arthur H. Peters, a citizen of the United States, residing at Fort Wayne, in the county of Allen, State of Indiana, have invented a new, original, and ornamental Design for a Combined Washing Machine Casing and Wringer, of which the following is a specification, reference being had to the accompanying drawing, forming part thereof.

Figure 1 is a front perspective view of my

combined washing machine casing and wringer, and

Figure 2 is a side perspective view thereof, with the wringer swung around to show the rear side.

I claim:

The ornamental design for a combined washing machine casing and wringer, as shown and described.

ARTHUR H. PETERS.
